UNITED STATES PATENT OFFICE

RAYMOND T. ANDERSON, OF CLEVELAND, OHIO, ASSIGNOR TO THE V. D. ANDERSON COMPANY, OF CLEVELAND, OHIO, A CORPORATION OF OHIO

PRESS

Application filed May 28, 1925. Serial No. 33,461.

This invention pertains to improvements in presses, and more particularly to that type set forth in U. S. Letters Patent to Anderson, Nos. 731,734; 731,735; and 731,737, dated June 23, 1903, wherein there is shown a shell with a series of separated screws mounted therein, which screws feed the material throughout the shell, compress the same, and force the liquid contents, such as oil or the like, therefrom. Working in conjunction with the outlet of the press, as shown in the patents above referred to, means is provided for retarding the outflow and causing the material to be held in the press or shell for the requisite period of time.

The present invention relates more particularly to the means for regulating the discharge from the press, and takes the place of the cone construction shown in Patent No. 731,734, or the head, shell or casing G' of Patent No. 731,735. Under the present invention, the choke as it may be termed, at the discharge end of the press is stationary in so far as any rotary movement is concerned, though it is adjustable to vary its effectiveness with relation to the discharge of the material, and such adjustment may be effected while the machine is in operation, whereas under the old construction where the cone was employed, it was necessary to stop the machine when adjustment was to be brought about. Furthermore, with the stationary choke of the present case, less friction obtains between the choke and the pressed cake being discharged from the expeller, with the result that the cake is lighter in color, which is a desirable feature. Under the old construction where the cone revolves and the cake is forced thereover, the cake becomes hot on account of the friction produced by revolving the cone under the extreme pressure which obtains in presses of this type. Furthermore, by the present construction the press is easier to repair, inasmuch as new parts can be installed without dismantling

the expeller, which dismantling was necessary under the old cone construction. Again, the present choke materially reduces the amount of machinery and gears required at the discharge end of the expeller over that which obtained under the old construction, or at least under the old commercial form, where the cone was employed.

Furthermore, the present structure eliminates the cone point and discharge collar with its attendant tendency to leak liquids under cone point and outside of discharge collar as in older forms of presses. In addition to the constructional advantages above set forth, it has been found that better extraction is effected and a gain as high as 2% obtains over the older forms.

The invention is illustrated in the annexed drawings, wherein,—

Fig. 1 is a longitudinal vertical sectional view of so much of a press as is necessary to the illustration of the invention;

Fig. 2 a vertical sectional view taken on the line II—II of Fig. 1;

Fig. 3 a similar view taken on line III—III of Fig. 1;

Fig. 4 a transverse horizontal sectional view taken on the line IV—IV of Fig. 3;

Fig. 5 a perspective view of the fixed guide member in which the inner ends of the jaws of the choke are mounted;

Fig. 6 a sectional perspective view of a portion of the housing;

Fig. 7 a like view of the combined gear ring and cam member employed to effect longitudinal adjustment of the jaws of the choke;

Fig. 8 a perspective view of one of the jaws;

Fig. 9 a similar view of the actuator therefor;

Fig. 10 a perspective view of another of the jaws;

Fig. 11 a like view of the actuator for said jaw; and

Fig. 12 a perspective view of the bearing members employed in connection with the

actuator and which take upon the cam surfaces formed upon the cam ring shown in Fig. 7.

Broadly stated, the choke may be said to comprise a plurality of members standing in radial relation to the shaft of the press, combined with means whereby said members may be moved or adjusted in a radial direction to enlarge or contract the discharge opening through which the material must pass as it is forced outwardly from the press by the screws.

The expressing means employed may be of any approved type, but I prefer that shown in the patents above referred to, and for the purpose of illustration there is shown in Fig. 1 so much of a barrel of the press, together with the screws, as is necessary to a clear understanding of the invention.

Referring to said figure, 1 denotes the shell of the press composed of a series of bars held in spaced relation to each other and forming a cylindrical barrel. These bars are backed up by suitable ribs, as 2, which prevent bursting of the shell under the high pressure to which it is subjected. The material to be treated is fed in, as through a hopper 3, and comes into working relation with the feeding screw 4, and is thereafter subjected to the compressive action of the screws or worms 5, all of which are carried upon and rotated with a shaft 6 driven by any suitable means (not shown).

The shaft at its outer end is supported in a suitable thrust bearing, designated generally by 7, which bearing in turn is secured upon the frame-work 8 of the machine. Said frame-work, as will be seen upon reference to Figs. 1 and 2, is made quite substantial, being suitably braced by ribs to withstand the strain. It has a semi-circular portion 9, the walls of which extend downwardly as at 10, forming a chamber into which the cake is discharged. The lower portion of the walls 8 and 10 bear upon the upper edge of a base 11 into which the cake is discharged, a pivoted gate 12 being mounted therein to deflect the cake to one or another conveyor or receptacle (not shown) as desired.

To the left of the base, beneath the shell, is the usual trough 13 and conveyor 14 for handling the foots.

Secured to the inner wall of frame or casting 8 is a housing 15 of the form best shown in Fig. 6. It is provided with a central inwardly extending hub section 16 and with a laterally extending flange 17, which members, together with the body, produce a seat and bearing for an annular combined worm gear 18 and adjusting member or actuator for the radially disposed elements of the adjustable choke.

Said housing is bolted to the frame member 8 and is likewise provided with perforate ears 18 (see Figs. 3 and 6) through which the

longitudinal bars 19 pass. These serve to support the frame member 8 when it is withdrawn to permit replacement of the choke blocks 31 and 41, hereinafter described.

Extending inwardly through the hub 16 is a block or member of the form best shown in Fig. 5—that is to say, it comprises plate-like member 20 having formed integral therewith a head or cylindrical member 21 provided with a series of radially disposed grooves or ways 22 formed therein, said ways extending entirely through the cylindrical portion and opening at their inner ends adjacent the central bore or opening 23 produced in the block or casting. Said member is secured to the outer face of the housing 15 and the inner ends of the member 21 are bolted to thrust plates 24 and 25 which are housed within the wall of the frame-work 8 of the machine, as will be best seen upon reference to Figs. 1 and 4. Located within the housing 15 is a worm ring or gear 26 (see more particularly Fig. 7) having an inwardly extending flange 27, which flange at its inner edge is thickened and provided with a series of cam faces 28 corresponding in outline to cam faces 29 formed upon the inner face of the body of the gear. These cam faces 28 and 29 are employed to actuate the radially disposed members of the choke and serve to move said members inwardly and outwardly toward or from the shaft 6, and more specifically, toward or from the sleeve 30 which surrounds the same adjacent the point of discharge of the cake from the shell of the press.

In the form illustrated there are six of the radially disposed and adjustable choke members. They are substantially alike in form, though the alternate ones are slightly modified in order that they may overlap and pass each other as they are moved inwardly or outwardly under adjustment. These choke blocks and their co-operating members which serve to move them inwardly and outwardly are best shown in Figs. 8 to 12 inclusive.

Referring first to Figs. 8 and 9, the choke block is designated by 31, and as will be seen is formed with an arcuate inner end or face 32 which, in addition to being curved or arcuate in outline, stands at an angle with reference to the axis of the machine (see Fig. 4). The block is provided in its outer face with a cross slot 33, and outwardly from said slot, the block is cut away upon a curve as at 34, so as to provide clearance for the material after it has passed the high end of the arcuate face 32. The actuator for this block is shown in Fig. 9, is designated generally by 35, and is provided at its inner end with a curved face 36 which, when the parts are assembled, alines with curved face 34, and is likewise provided upon its side with two transversely extending lugs or ribs 37 and 38. Lug 37, when the parts are positioned (see Fig. 4) extends into the cross groove or

channel 33, while the lug 38 extends across the outer end of the block 31 and backs the same up against outward thrust during the action of the press. The outer end of the actuator member 35 is slightly enlarged and is provided with a transverse opening in which is mounted a cylindrical bearing element 39. The outer end of the actuator member 35 is formed with a semi-circular recess in which is seated a half-round or substantially half-round bearing block 40, the outer slightly curved flattened face of which, when the parts are assembled, bears directly and fully against its corresponding cam 29, while the round member 39 takes against the relatively narrower cam 28. Inasmuch as the member 39 and the cam 28 are merely employed to retract the actuator 35 and its choke block, the small cam bearing is all sufficient. The wider cam face 29, however, takes up the thrust and is therefore made quite substantial. The actuator member 35 passes through the oppositely disposed channel or guide 22 formed in the hub section heretofore referred to.

The other form of actuator and choke block are shown in Figs. 10 and 11. The choke block in this instance is, as compared to the block heretofore described, relatively thin or flat. (See also Fig. 4.) The block is designated by 41 and is provided with a curved and beveled or inclined face 32^a corresponding to the face 32 of the other block, and likewise has formed in its side face a transverse groove or channel 33^a. The actuator is designated by 35^a and is provided with a transverse rib 37^a and a shoulder 38^a, these parts corresponding in function to the parts 37 and 38. The inner end is curved and beveled or inclined as at 36^a to provide clearance for the discharged cake. The same bearing elements 39 and 40 are present as in the other form of actuator and co-operate with the inner and outer cams 28 and 29 respectively. When the parts are assembled, the rib 37^a finds its seat within the groove 33^a and the shoulder 38^a takes against the outer end of the choke block 41 and backs the same up against outward thrust.

As will be readily appreciated upon an inspection of Figs. 3 and 4, rotation of the worm gear 26 in one or another direction will cause an inward or outward movement of the actuators 35 and 35^a and the respective choke blocks which are attached thereto. By offsetting the alternate blocks, they may be moved inwardly and pass each other without interference, and thus be brought to the desired adjusted relation with reference to the sleeve 30 which surrounds the shaft of the press.

To effect a proper adjustment of these choke blocks and to hold them in their adjusted position, there is employed a worm 42 mounted in a suitable housing, as 43, said

worm meshing with the worm gear 26. Motion may be imparted to this worm 42 through any suitable mechanism, and in the instant case, such motion is shown as being imparted through a second worm wheel 44 (Figs. 2 and 3) secured to the shaft of the worm 42, and motion is imparted to the worm wheel 44 through a worm 45. To the shaft of this worm is secured a hub 46 carrying a series of hand arms or levers 47 through which motion may be applied to the gear train.

In order to break up the cake as it is discharged from the press, or after it leaves the choke formed of the various choke blocks as above described, there is provided a stud 48 (Fig. 1) which is secured in a sleeve 42 mounted outwardly of the sleeve 30 and the choke, and rotatable with the shaft 6. Said stud, by reason of its rotation with the shaft and sleeve, projects into the extruding cake as it passes outwardly from the choke and breaks it up. When located in the position shown in Fig. 1, the cake is broken up into relatively small pieces. By locating the stud outwardly from the choke to a greater extent than that shown, the cake will not be so finely broken up or divided by the stud.

With the construction as above described, adjustment of the choke may be had while the machine is in operation, and the various choke blocks moved inwardly and outwardly simultaneously and to the same extent or degree. Thus the discharge of the cake may be easily regulated, a point of manifest advantage and one which is necessary when treating different classes of material. Furthermore, the blocks may be readily replaced without dismantling the press and removing the outer thrust bearing 7 as is necessary where a cone choke is employed, as in the patented structures above mentioned.

In so far as the underlying or generic invention is concerned, it is conceivable that the choke blocks may be independently adjusted toward and from the discharge opening of the press, such construction being shown, however, in my co-pending application, Serial No. 101,507, filed on or about April 26, 1926.

What is claimed is:

1. In a press the combination of a casing having openings therein for the passage of expressed liquid; means working in the casing to subject the material undergoing treatment to pressure and to advance the pressed material toward the discharge end of the press; a plurality of laterally adjustable members, the inner ends whereof extend into the discharge opening, said members producing a choke for said opening; and means for securing simultaneous adjustment of said members and maintaining them in their adjusted position.
2. In a press the combination of a casing,

- a rotatable shaft extending therethrough; means carried by the shaft for subjecting the material undergoing treatment to pressure and to advance the same through the casing; a series of adjustable jaws extending inwardly toward the shaft at the discharge end of the casing to produce a choke for the material about the shaft; and means for holding said jaws in their adjusted position.
3. In a press the combination of a casing; a rotatable shaft extending therethrough; means carried by the shaft for subjecting the material undergoing treatment to pressure and to force the same outwardly from the discharge end of the casing; a series of radially disposed jaws located at the discharge end of the casing; and means for simultaneously adjusting said jaws toward and from the shaft and thereby varying the area of the discharge opening.
- 10 4. In a press the combination of a casing; a rotatable shaft extending therethrough; means carried by the shaft for subjecting the material undergoing treatment to pressure and to force the same outwardly from the discharge end of the casing; a series of radially disposed jaws located at the discharge end of the casing; cams connected to the outer portions of said jaws; and means for actuating said cams to effect an inward or outward adjustment of the jaws.
- 15 5. In a press the combination of a casing; a rotatable shaft extending therethrough; means carried by the shaft for subjecting the material undergoing treatment to pressure and to force the same outwardly from the discharge end of the casing; a series of radially disposed jaws located at the discharge end of the casing; a worm gear mounted for rotation in a plane at right angles to the shaft; a series of cams formed upon the inner portion of said gear and with which the jaws are in engagement; and a worm meshing with the gear.
- 20 6. In a press the combination of a casing; a rotatable shaft extending therethrough; means carried by the shaft for subjecting material to pressure and forcing the same longitudinally of the casing; radially disposed guideways located at the discharge end of the casing; an actuator mounted in each way; a jaw engaged with the inner end of each actuator; a worm gear mounted for rotation in a plane at right angles to the shaft; a series of cams formed upon the inner portion of the same and with which the actuators are in engagement; and a worm meshing with the gear.
- 25 7. In a press the combination of a casing; a rotatable shaft extending therethrough; means carried by the shaft for subjecting material to pressure and forcing the same longitudinally of the casing; radially disposed guideways located at the discharge end of the casing; a ring-shaped member mounted for rotation in a plane at right angles to the shaft and in the plane of said guide-ways; a series of cams on the inner portion of said ring-shaped member; an actuator mounted in each guide-way and engaging the adjacent cam; and a jaw attached to the inner end of each actuator, each alternate jaw being off-set with relation to those next adjacent whereby the jaws may overlap at their inner ends.
- 30 8. In testimony whereof I have signed my name to this specification.
- 9 RAYMOND T. ANDERSON.
